BORE SIGHT

Herman P. Kaufman, United States Army, Washington, D. C., and Douglas L. Parkhurst, Springfield, Mass.

Application June 2, 1941, Serial No. 396,286

3 Claims. (Cl. 33—46)

(Granted under the act of March 3, 1883, as amended April 30, 1928; 370 O. G. 757)

The invention described herein may be manufactured and used by or for the Government for governmental purposes, without the payment to us of any royalty thereon.

This invention relates to a telescopic bore sight.

A principal object of the invention is to provide a simple telescope mounting adapted for use in accurately mounting a telescope in the chamber of a gun with its optical axis coinciding with the axis of the bore of the gun.

A further object of the invention is to provide a bore sight mounting adapted to be positioned in the chamber of any gun of the same caliber in such manner as to accurately position the axis of the bore sight in coincident relation with the axis of the bore of the gun.

The specific nature of the invention as well as other objects and advantages thereof will clearly appear from a description of a preferred embodiment as shown in the accompanying drawing in which:

Fig. 1 is a longitudinal sectional view through the breech end portion of a gun showing the bore sight of this invention, also in longitudinal section, mounted in the chamber thereof.

Fig. 2 is a sectional view taken upon the line 2—2 of Fig. 1.

Referring now to the drawing, and more particularly to Fig. 1, there is shown the breech end portion of a gun 10 provided with a conventional cartridge chamber 11 of generally truncated conical form. The bore sight of this invention, generally indicated at 12, is mounted in the chamber 11 with its axis 13 in coincident relation to the axis 14 of the bore of the gun by means of a tubular bore sight mounting member 15 provided with a concentrically disposed outwardly protruding flange or other suitable support 16 adjacent its forward end adapted to engage a complementary section of the chamber 11 concentrically of the axis thereof. The rear end portion of the mounting member 15 is of reduced section as indicated at 17 to form a shoulder 18 intermediate its ends.

A tubular element 19 is mounted upon the 45 reduced section 17 of the mounting member 15 for adjustable sliding movement coaxially of the member 15 between a forward position of abutment with the shoulder 18 and any desired position rearwardly of the forward position. The 50 element 19 is formed with a concentric outwardly protruding flange or other suitable support 20 of somewhat larger diameter than the flange 16 for engaging the adjacent portion of chamber 11 in a manner to support member 15 coaxially of the 55

axis 14 of the bore and chamber of the gun. Conveniently the flange 20 is located intermediate the ends of the tubular element 19 and the latter may be provided with a suitable finger piece adjacent its rear end to facilitate adjustment of the element for adapting the flange 20 to concentrically engage the chamber wall when used in various guns having chambers 11 of different degrees of conicity.

10 The telescopic bore sight 12 comprises the usual objective 21, telescope tube 22, adjustable eyepiece 23 and reticle 24 and is arranged with its objective end portion disposed within the mounting member 15 in a supported position with its axis 13 disposed coaxially of the member 15. To facilitate positioning of the bore sight in proper position within the member 15 the tube 22 thereof may be formed with a flange 25 or other suitable stop element to engage the outer end of the member 15.

Having now described a present preferred embodiment of the invention, we claim:

1. In a bore sight for a gun having a generally truncated conical chamber, a tubular sight 25 mounting member adapted to mount a bore sight on the interior thereof formed to provide a surface adapted to concentrically engage a complementary wall section of said chamber adjacent the small end of the latter, an element mounted upon the mounting member for coaxial sliding movement thereon, said element being formed with concentric means for engaging a complementary wall section of said chamber spaced from said first named complementary wall section; whereby said sight may be arranged in the chamber with its axis in coincident relation to the axis of the chamber.

2. In a bore sight for a gun having a generally truncated conical chamber, a tubular sight 30 mounting member, an outwardly protruding concentric support formed on said member adjacent its forward end adapted to engage a complementary wall section of said chamber, a tubular element mounted upon the rear end portion of the member for coaxial sliding movement thereon, said element being formed with an outwardly protruding concentric support surface for engaging a complementary wall section of said chamber rearwardly spaced from said first named complementary wall section; whereby said sight may be arranged in the chamber with its axis in coincident relation to the axis of the chamber.

3. In a bore sight for a gun having a generally truncated conical chamber, a tubular sight 35 mounting member provided with a rear end por-

tion of outside reduced section, said mounting member being provided with an outwardly protruding concentric flange adjacent its forward end adapted to engage a complementary wall section of said chamber, a tubular element mounted upon said portion of reduced section of the mounting member for coaxial sliding movement, said element being formed with an outwardly protruding concentric flange of larger

5 diameter than said flange on the mounting member for engaging a complementary wall section of said chamber rearwardly spaced from said first named complementary wall section; whereby said sight may be arranged in the chamber with its axis in coincident relation to the axis of the chamber.
